COMBINED EASEL AND WORK SUPPORT STAND THEREFOR

Frank R. Torrey, 9805 Dallas Ave.,
Silver Spring, Md. 20901

Filed Feb. 19, 1971, Ser. No. 117,179

Term of patent 14 years

Int. Cl. D6—03

U.S. Cl. D6—181

FIG. 1

FIG. 3

FIG. 1 is a perspective view of a combined easel and work support stand therefor, showing my new design;

FIG. 2 is a right side elevational view thereof, the left side being a mirror image thereof, and

FIG. 3 is a top plan view thereof.

I claim:

The ornamental design for a combined easel and work support stand therefor, as shown and described.
